UNITED STATES PATENT OFFICE.

OSCAR B. CLAYTON, OF HOUSTON HEIGHTS, TEXAS.

OIL-BURNER.

1,085,581.

Specification of Letters Patent. Patented Jan. 27, 1914.

Application filed April 27, 1912. Serial No. 693,540.

To all whom it may concern:

Be it known that I, OSCAR B. CLAYTON, a citizen of the United States, residing at Houston Heights, in the county of Harris and State of Texas, have invented certain new and useful Improvements in Oil-Burners, of which the following is a specification.

My invention relates to new and useful improvements in oil burners.

10 This burner belongs to that class of burners, wherein the fuel oil is sprayed through the discharge nozzle by means of steam pressure, the steam being formed in a heating coil and discharged through the nozzle in the 15 well known manner, and the object of this invention is to provide a burner of the character described whereby the water supplied to the coil, the fuel supplied to the burner and the discharge of the steam through the 20 nozzle may be simultaneously regulated so that as the fuel supply is increased, the water supplied to the coil will be correspondingly increased and the nozzle opening for the steam discharge be also correspondingly 25 increased.

With the above and other objects in view, the invention has particular relation to certain novel features of construction, operation and arrangement of parts, an example of 30 which is given in this specification and illustrated in the accompanying drawings, wherein—

Figure 1 is a sectional plan view of the burner, and Fig. 2 is a side elevation thereof. 35 Referring now more particularly to the drawing, wherein like numerals of reference designate similar parts in each of the figures, the numeral 1 refers to a block which composes the body of the burner and which is 40 formed of any suitable material. One end of this block carries the discharge nozzle 2 having a tapering free end with a discharge outlet 3. Alined with the outlet 3 and extending entirely through the block is a needle 45 valve 4 which is provided with a lengthwise fuel passage way 5 extending from end to end thereof. The free end of the needle valve 4 is tapering and is designed to control the nozzle outlet 3. The other end of the 50 block 1 carries a supporting sleeve 6 which is integral with the block and which is in alinement with the nozzle 2. This sleeve is provided with a transverse slot 7 in which the transverse arm 8 is designed to slide. 55 The needle valve 4 is threaded into the center of this arm.

To the ends of the arm 8 are secured, respectively, the needle valves 9 and 10, the former of which controls the flow of water from the water supply to the steam generating coil 10', and the latter of which controls the supply of fuel oil from the oil supply to the burner nozzle. The water from which the steam is formed is supplied from any suitable source through the water pipe 65 11 to the passageway 12 which extends through the block 1 into the chamber 13. From this chamber, the water passes through the passageway 14 to the passage way 15 which leads to the coil where it is formed 70 into steam in the usual manner and the steam is delivered through the passage 16 from said coil into the burner nozzle 2 and discharged through the opening 3 around the tapering end of the needle valve 4. The 75 needle valve 9 extends through a stuffing box 17, carried by the block 1, to the chamber 13 and its tapering free end is arranged to control the discharge of the passage way 12 into the chamber 13. 80

The fuel oil is fed from any suitable supply through the pipe 18 into the passageway 19 which extends through block 1 and communicates with chamber 20 in said block. The needle valve 10 passes through a suitable stuffing box 21 carried by the block 1 and its tapering free end extends into the chamber 20 and is alined with the passageway 19 and controls the discharge of fuel from said passageway into said chamber. 90 The needle valve is provided with a lengthwise passageway 22, which extends from the orifice 23, near the free end thereof, entirely to the other end and connects with a passageway 24 in the arm 8. This last mentioned passageway extends through said arm and connects with the passageway 5 of the needle valve 4. The fuel is admitted through the pipe 18 and passage way 19 into the chamber 20 and passes thence through the 100 orifice 23 along the passageway 22 of the needle valve 10 into the passageway 24 and thence through the needle valve 4 to the discharge nozzle. 95

A hand screw 25 is threaded through the 105 outer end 26 of the sleeve 6 and its inner end engages with the arm 8, as shown, and by a manipulation of said screw, the said arm 8 may be moved in either direction in the slot 7 and the position of the needle valves 4, 9 110 and 10 thus regulated and the supply of water to the coil and fuel to the burner nozzle.

zle thus controlled and simultaneously therewith the nozzle opening 3 enlarged or contracted.

The fuel discharged through the burner nozzle is sprayed by the steam escaping through the nozzle opening 3 and it is the object of this invention to provide a burner whereby as the fuel supply is increased, the spraying jet of steam will also be increased 10 and a uniform fuel spray will thus be provided whether there is a large or small supply of fuel to the burner nozzle.

The numeral 27 refers to a cylindrical shaped muffler, which is shown partially 15 broken away. This muffler is not essential, but may be used to muffle the roar caused by the combustion of the fuel spray around the nozzle 3.

What I claim is:—

20 1. A device of the character described including a block and a nozzle carried thereby, a needle valve passing through said block and alined with the nozzle and having a passageway therethrough, a fuel passageway extending through said block and communicating with the passageway in said valve, a water passageway extending through said block, valves controlling said fuel and water passageways, means for simultaneously operating all of said valves and a steam generator communicating with said water passageway and discharging steam into said nozzle and around the valve alined therewith.

35 2. A device of the character described, including a suitable block having a water passageway and a fuel passageway extending therethrough, a burner nozzle carried by the block, a valve extending through the block 40 and alined with the nozzle and having a passageway extending therethrough, a valve controlling said fuel passageway, said last mentioned valve having a lengthwise passageway extending therethrough and communicating with the passageway of the nozzle 45 controlling valve so as to admit fuel from said fuel passageway through said last mentioned valve, a means for simultaneously operating both of said valves, and a steam generator having communication with the water 50 passageway and discharging steam into the nozzle and around the nozzle controlling valve.

55 3. A device of the character described consisting of a block having a water passageway and a fuel passageway extending therethrough, a discharge nozzle carried by said block provided with a discharge outlet, a needle valve extending through the block 60 and passing axially through the nozzle and having its free end projecting into said outlet, said needle valve having a lengthwise passageway therethrough which communicates with the fuel passageway, a supporting 65 sleeve carried by the block on the opposite

side thereof from said nozzle and provided with a lengthwise slot therein, an arm slideable in said slot, to the central portion of which said needle valve is secured, needle valves carried by the ends of said arm, whose free ends, respectively, project into said water passageway and fuel passageway and control the flow of fluid therethrough, a mechanism connected to said arm for adjusting the same in the slot of said sleeve, 70 and a steam generating mechanism communicating with the water passageway and discharging steam into the nozzle and around the nozzle controlling valve. 75

4. A device of the character described, including a block having a water passageway and a fuel passageway extending therethrough, a discharge nozzle carried by one end of said block and provided with a discharge outlet, a needle valve extending 80 through the block and passing axially through the nozzle whose free end controls the nozzle outlet, said needle valve having a lengthwise passageway extending therethrough, a supporting sleeve carried by the 85 block on the opposite side thereof from said nozzle and provided with a lengthwise slot therein, an arm slideable in said slot, to the central portion of which said needle valve is secured, said arm having a lengthwise passageway therein which communicates with the passageway of said needle valve, a needle valve carried by one end of said arm whose free end passes into said block and projects into the water passageway and controls the flow of water therethrough, a needle valve carried by the other 90 end of said block whose free end passes into said block and projects into the fuel passageway and controls the flow of fuel therethrough, said last mentioned valve being provided with an internal passageway, one 95 end of which communicates with the fuel passageway and the other end of which communicates with the passageway in said arm, a means for adjusting said arm and thereby controlling the position of said needle valves, and a steam generating mechanism communicating with the water passageway and discharging into said nozzle. 100

105 5. A device of the character described consisting of a block having a water passageway and a fuel passageway extending therethrough, a discharge nozzle carried by said block provided with a discharge outlet, a 110 hollow needle valve extending through the block and passing axially through the nozzle and having its free end projecting into said outlet, the interior of said valve communicating with said fuel passageway, a 115 supporting sleeve carried by the block on the opposite side thereof from said nozzle and provided with a lengthwise slot therein, an arm slideable in said slot, to the central portion of which said needle valve is se- 120

125

- cured, needle valves carried by the ends of said arm, whose free ends, respectively, project into said water passageway and fuel passageway and control the flow of fluid therethrough, a mechanism connected to said arm for adjusting the same in the slot of said sleeve, and a steam generator communicating with said water passageway and discharging into the discharge nozzle.
- 5 6. A device of the character described, including a block having a water passageway and a fuel passageway extending therethrough, a discharge nozzle carried by one end of said block and provided with a discharge outlet, a needle valve extending through the block and passing axially through the nozzle whose free end controls the nozzle outlet, said needle valve having a lengthwise passageway extending there- 10 through, a supporting sleeve carried by the block on the opposite side thereof from said nozzle and provided with a lengthwise slot therein, an arm slideable in said slot, to the central portion of which said needle valve
- is secured, said arm having a lengthwise passageway therein which communicates with the passageway of said needle valve, a needle valve carried by one end of said arm whose free end passes into said block and projects into the fuel passageway and controls the flow of fuel therethrough, said last mentioned valve being provided with an internal passageway, one end of which communicates with the fuel passageway in said arm, a means for adjusting said arm and thereby controlling the position of said needle valves, and a steam generator communicating with said water passageway and discharging into the interior of the discharge nozzle.
- 15 7. In testimony whereof I have signed my name to this specification in the presence of two subscribing witnesses.
- 20 OSCAR B. CLAYTON.
